Des. 181,142
Patented Oct. 8, 1957

181,142

ELECTRIC MOTOR

Hugo Grote, Wetter (Ruhr), Germany, assignor to Demag-Zug G. m. b. H., Wetter (Ruhr), Germany

Application August 10, 1955, Serial No. 37,403

Claims priority, application Germany May 3, 1955

Term of patent 14 years

(Cl. D26—5)

FIG. 1.

FIG. 2.

FIG. 3.

Des. 181,142

PAGE 2

FIG. 4.

FIG. 5.

FIG. 6.

Fig. 1 is a top plan view of an electric motor, showing my new design;

Fig. 2 is a side elevational view thereof;

Fig. 3 is a bottom plan view thereof;

Fig. 4 is an end view thereof looking at the left end in Fig. 1;

Fig. 5 is an end view thereof, looking at the right end in Fig. 1; and

Fig. 6 is a side elevational view thereof, showing the side opposite that shown in Fig. 2.

I claim:

The ornamental design for an electric motor, as shown.
